(57) **CLAIM**

The ornamental design for a combined bucket with bail attachment, as shown and described.

DESCRIPTION

FIG. 1 is a perspective view of a combined bucket with bail attachment, shown with the bail attachment removed for clarity of disclosure;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof;

FIG. 7 is a perspective view of the combined bucket with bail attachment;

FIG. 8 is a top plan view thereof;

FIG. 9 is a front elevational view thereof;

FIG. 10 is a rear elevational view thereof;

FIG. 11 is a bottom plan view thereof; and,

FIG. 12 is a left side elevational view thereof.
